HOUSING FOR A TELEVISION RECEIVER

Geoffrey H. Bruce, Schoolhouse and Grapevine Roads,
Cavecreek, Ariz. 85331

Filed Oct. 19, 1966, Ser. No. 4,344

Term of patent 14 years

(Cl. D56—4)

Fig. 1.

Fig. 2.

Fig. 3.

Fig. 4.

Fig. 5.

Fig. 6.

FIG. 1 is a right side, top, and front perspective view of a housing for a television receiver, showing one form of my new design wherein the housing is generally in the form of a predominant part of a sphere, the front face of the housing is generally flat, is slanted rearwardly and upwardly, at a small angle relatively to the vertical, and has a diameter substantially exceeding the radius of the spherical portion of the housing, the housing has a visible line generally in the form of a great circle of the spherical portion of the housing, such line lying in a plane which is inclined upwardly and rearwardly at generally a 45° angle, and substantially the full area of the front, plane surface of the housing is occupied by a transparent plate or sheet, the housing being supported on a centrally disposed vertical cylindrical leg projecting from a flat square base;

FIG. 2 is a front elevational view of the form shown in FIG. 1;

FIG. 3 is a right side elevational view of the form shown in FIG. 1, the opposite side being substantially a mirror image thereof;

FIG. 4 is a top plan view of the form shown in FIG. 1;

FIG. 5 is a right side elevational view of a housing for a television receiver, showing a second form of my new design wherein the housing is generally in the form of a predominant part of a sphere, the front face of the housing is generally flat, is slanted rearwardly and upwardly at a small angle relatively to the vertical, and has a diameter substantially exceeding the radius of the spherical portion of the housing, the housing has a visible line generally in the form of a great circle of the spherical portion of the housing, such line lying in a plane which is inclined upwardly and rearwardly at generally a 45° angle, and substantially the full area of the front, plane surface of the housing is occupied by a transparent plate or sheet, the housing being supported on the flat surface formed by slicing a horizontal section from the sphere, the opposite side being substantially a mirror image thereof; and

FIG. 6 is a bottom plan view of the form shown in FIG. 5.

The front and top of the form shown in FIGS. 5 and 6 are similar to the same portions of FIGS. 2 and 4, respectively.

The characteristic features of my new design reside in the making of the housing generally in the form of a predominant part of a sphere, the making of the front face of the housing generally flat and slanted rearwardly and upwardly at a small angle relatively to the vertical, the making of the flat front face of the housing with a diameter which substantially exceeds the radius of the spherical portion of the housing, the provision of a visible line generally in the form of a great circle of the spherical portion of the housing, such line lying in a plane which is inclined upwardly and rearwardly at generally a 45° angle, and the use of a transparent plate or sheet which occupies substantially the full area of the front plane surface of the housing.

I claim:

The ornamental design for a housing for a television receiver, as shown and described.
